UNITED STATES PATENT OFFICE

2,233,197

RAILWAY VEHICLE

Basil S. Cain, Erie, Pa., assignor to General Electric Company, a corporation of New York

Application May 1, 1940, Serial No. 332,741

7 Claims. (Cl. 105—396)

My invention relates to railway vehicles, and particularly to an improved vehicle body construction.

An object of my invention is to provide an improved railway vehicle body construction.

Another object of my invention is to provide an improved railway vehicle body frame construction.

Further objects and advantages of my invention will become apparent and my invention will be better understood from the following description referring to the accompanying drawings, and the features of novelty which characterize my invention will be pointed out with particularity in the claims annexed to and forming part of this specification.

In the drawings, Fig. 1 is a side elevational view of a locomotive embodying my improved body and frame construction, partly broken away to illustrate the arrangement of the frame at the back end thereof; Fig. 2 is a plan view of the locomotive shown in Fig. 1, partly broken away adjacent the back end thereof to show the body construction at this end; Fig. 3 is an enlarged side elevational view, partly broken away, of sections of the locomotive frame shown in Fig. 1 illustrating the relative arrangement of the frame construction at the front and at the back ends of the locomotive; Fig. 4 is an enlarged partial sectional plan view of the locomotive frame shown in Fig. 2, taken along line 4—4 of Fig. 3 and partly broken away to show the relative arrangement of the locomotive body and frame construction at the front and back ends of the locomotive; Fig. 5 is an elevational sectional view taken along 5—5 of Fig. 4; and Fig. 6 is a sectional end elevational view taken along line 6—6 of Fig. 3.

Referring to the drawings, I have shown a railway locomotive which is adapted to be supported on a pair of main driving trucks 10 provided with driving wheels 11 and provided with guiding and trailing trucks 12 and 13 arranged respectively at the front and back ends of the locomotive. These trucks are arranged to support the locomotive superstructure which comprises a plurality of compartments arranged to house the locomotive power and control equipment and the fuel supply.

In many modern high speed locomotives, it has been found desirable to provide heat transfer devices such as radiators or condensers for cooling engine cooling water or exhaust steam, and it is necessary to provide an arrangement which will supply an adequate ventilating medium circula-

tion to remove the heat from these heat-transfer devices. I have found it desirable and advantageous to arrange the heat-transfer devices adjacent an outer surface of the locomotive and to provide a supporting frame for the locomotive superstructure which will not interfere with the proper cooling and operation of these heat-transfer devices. In order to support the outer locomotive wall surface of the front portion of the locomotive, I provide a plurality of load-supporting truss elements adjacent each side thereof, including upwardly extending posts 14 connected together by diagonally extending brace elements 15 which are secured to the posts 14 by gusset plates 16 and 17. The upper and lower ends of the posts 14 and the braces 15 also are secured together by longitudinally extending beams 18 which also are reinforced by being securely welded to the gusset plates 16 and 17. In order to provide a more rigid transverse frame construction, I arrange transversely extending beams 19 between the truss elements on opposite sides of the locomotive and securely weld these beams 19 to the side frame load-carrying truss elements. The lower portion of the frame also is rigidly secured together by a plurality of transversely extending angle beams 20 over which floor plates 21 are arranged. The floor plates 21 form the upper surface of an air distributing duct which is closed on its lower side by lower plates 22 secured to the under side of the transversely extending beams 20. A plurality of the load-carrying trusses is arranged adjacent each side of the locomotive for a given length thereof extending from the front end of the locomotive substantially to the point at which the heat-transfer devices are to be arranged. These truss elements are arranged in substantially parallel aligned relationship longitudinally of the vehicle and outer wall plates 23 are secured thereto to provide an outer wall surface for the vehicle. A roof structure 24 also is secured to the upper transversely extending beams 19 in order to provide a suitable cover for the locomotive equipment.

In the illustrated construction, the heat exchange device is arranged adjacent the back end of the locomotive, and it has been found desirable to arrange louvers 25 to regulate the flow of air into these devices. These louvers 25 are arranged substantially in alignment with the outer wall 23 at the forward part of the locomotive and it therefore is desirable to arrange a supporting truss frame as in the forward end offset from these louvers. Such a frame is arranged spaced inwardly from the louvers, and includes a plural-

ity of load-carrying truss elements comprising upwardly extending posts 26 secured together by diagonally extending brace elements 27 and a longitudinally extending beam 28 secured to the upper ends of the posts 26 and to the diagonally extending braces 27. A plurality of these load-carrying truss elements is arranged along each side of the vehicle spaced inwardly from the truss elements at the front end of the vehicle, so as to provide a transversely offset frame, which is substantially parallel to the frame at the forward end of the locomotive. The upper ends of the truss elements on opposite sides of the vehicle are secured together by transversely extending angle irons 29 and the lower ends of the truss elements on opposite sides of the locomotive are rigidly secured together by transversely extending channel beams 30. Floor plates 31 are arranged over the channel beams 30 and are securely welded thereto. The outer wall surface at the back end of the locomotive is formed by upper and lower plates 32 and 33 and by the upwardly extending louver elements 25. This outer vehicle surface is, therefore, arranged in transversely spaced relation with respect to the truss elements at the back end of the locomotive and provides a compartment therebetween in which the heat-transfer devices may be arranged. I provide reinforcing supporting plates 34 which extend between the posts 26 and the outer wall plate 32 to provide an arrangement for supporting the upper end of the louvers 25. In this arrangement, the truss elements adjacent the heat-transfer devices extend substantially from the back end of the locomotive for a predetermined length thereof to a point substantially opposite the end of the truss elements which form the longitudinally extending frame in the front portion of the locomotive. In transferring forces from one frame to the other of this offset truss construction, it is necessary to carry both tension and compression at the top and bottom connection, as well as shearing forces therebetween. In order to balance the moments of forces at the connection between the frames of each pair, I provide a triangulated cross truss construction including shear plates 35 extending transversely between the two frames of each pair at their adjacent ends and cross trusses or brace elements 36 and 37 at the top and bottom of the frames. These triangulating cross trusses 36 and 37 extend between the second post 14 from the end of the frame section at the front portion and the first post 26 of the frame section at the back portion of the locomotive and from this post 26 to the channel member 19 extending between the second post 14 on each side of the locomotive, respectively, to provide a rigid interconnected load-carrying unitary frame structure.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States, is:

1. A railway vehicle including a body having a frame comprising a plurality of main load carrying truss elements extending in substantially parallel aligned relationship for a given length through said vehicle adjacent each side thereof,

a second plurality of main load carrying truss elements extending in substantially parallel aligned relationship for another given length through said vehicle, said second plurality of truss elements being transversely offset and out of alignment with said first mentioned plurality of truss elements, and means arranged in transversely spaced relationship relatively to said second plurality of truss elements for providing an outer surface for said other given length of said vehicle and for providing a compartment between said outer surface and said second plurality of truss elements.

2. A railway vehicle including a body having a frame comprising a plurality of main load carrying truss elements extending in substantially parallel aligned relationship forming a frame section for a given length through said vehicle adjacent each side thereof, a second plurality of main load carrying truss elements extending in substantially aligned relationship for another given length through said vehicle, said second plurality of truss elements being transversely offset and out of alignment with said first-mentioned plurality of truss elements and forming a second frame section extending substantially from one end of said first-mentioned plurality of truss elements to the other end of said vehicle, triangulated means for rigidly securing together the truss elements of said two frame sections, and means arranged in transversely spaced relationship relatively to said second plurality of truss elements for providing an outer surface for said other given length of said vehicle and for providing a compartment between said outer surface and said second plurality of truss elements.

3. A railway vehicle including a body having a frame comprising a plurality of main load carrying truss elements extending in substantially parallel aligned relationship for a given length through said vehicle from one end thereof and adjacent each side thereof, a second plurality of main load carrying truss elements extending in substantially parallel aligned relationship for another given length through said vehicle from the other end thereof substantially to the adjacent end of said first-mentioned truss elements, said second plurality of truss elements being transversely offset and substantially parallel with said first-mentioned plurality of truss elements, and means arranged in transversely spaced relationship relatively to said second plurality of truss elements and substantially in alignment therewith for providing an outer surface for said other given length of said vehicle and for providing a compartment between said outer surface and said second plurality of truss elements.

4. A railway vehicle including a body having a frame comprising a plurality of main load carrying truss elements extending in substantially parallel aligned relationship for a given length through said vehicle adjacent each side thereof, a second plurality of main load carrying truss elements extending in substantially parallel aligned relationship for another given length through said vehicle, said second plurality of truss elements being transversely offset and substantially parallel to said first-mentioned plurality of truss elements along each side of said vehicle, means for transversely connecting together the truss elements along opposite sides of said vehicle, and means arranged in transversely spaced relationship relatively to said second plurality of truss elements for providing an outer surface for said other given length of said vehicle and for pro-

viding a compartment between said outer surface and said second plurality of truss elements.

5. A railway vehicle including a body having a frame comprising a plurality of main load carrying truss elements extending in substantially parallel aligned relationship for a given length through said vehicle adjacent each side thereof, a second plurality of main load carrying truss elements extending in substantially parallel 10 aligned relationship for another given length through said vehicle, said second plurality of truss elements being transversely offset and out of alignment with said first-mentioned plurality of truss elements, means connecting together said 15 first-mentioned and said second plurality of truss elements, means connecting together said truss elements on opposite sides of said vehicle, and means arranged in transversely spaced relationship relatively to said second plurality of truss 20 elements and substantially in alignment therewith for providing an outer surface for said other given length of said vehicle and for providing a compartment between said outer surface and said second plurality of truss elements.

25. 6. A railway vehicle including a body having a frame comprising a plurality of main load carrying truss elements extending in substantially parallel aligned relationship for a given length through said vehicle adjacent each side thereof, a second plurality of main load carrying truss elements extending in substantially parallel aligned relationship for another given length through said vehicle, said second plurality of truss elements being transversely offset and out 30 of alignment with said first-mentioned plurality of truss elements, means arranged about said 35

first-mentioned plurality of truss elements for providing an outer wall surface thereabout, and means arranged in transversely spaced relationship relatively to said second plurality of truss elements and substantially in alignment with 5 said wall for providing an outer surface for said other given length of said vehicle and for providing a compartment between said outer surface and said second plurality of truss elements.

7. A railway vehicle including a body having a 10 frame comprising a plurality of main load carrying truss elements extending in substantially parallel aligned relationship for a given length through said vehicle adjacent each side thereof, a second plurality of main load carrying truss 15 elements extending in substantially parallel aligned relationship for another given length through said vehicle, said second plurality of truss elements being transversely offset and out of alignment with said first-mentioned plurality of truss elements, transversely extending 20 means connecting together said truss elements on opposite sides of said vehicle adjacent the upper and lower ends thereof, means arranged about said first-mentioned plurality of truss 25 elements for providing an outer wall surface thereabout, and means arranged in transversely spaced relationship relatively to said second plurality of truss elements and substantially in alignment with said wall for providing an outer 30 surface for said other given length of said vehicle and for providing a compartment between said outer surface and said second plurality of truss elements.
